MARK B. CRIST, OF PITTSBURGH, PENNSYLVANIA, ASSIGNOR, BY MESNE ASSIGNMENTS, TO THE COLONIAL TRUST COMPANY, TRUSTEE, OF PITTSBURGH, PENNSYLVANIA, A CORPORATION OF PENNSYLVANIA.

JUMP-SPARK IGNITION APPARATUS FOR INTERNAL-COMBUSTION ENGINES.

1,089,461.

Specification of Letters Patent. Patented Mar. 10, 1914.

Application filed February 15, 1906. Serial No. 301,227.

To all whom it may concern:

Be it known that I, MARK B. CRIST, a citizen of the United States, and a resident of Pittsburgh, in the county of Allegheny and State of Pennsylvania, have made a new and useful Invention in Jump-Spark Ignition Apparatus for Internal-Combustion Engines, of which the following is a specification.

10 This invention relates to jump-spark ignition apparatus for internal combustion engines and has for an object the production of an apparatus simple in construction and effective in operation.

15 A further object is the production of a transformer adapted to be utilized in connection with the ignition apparatus and in which simple means are utilized for insulating and cooling the various parts.

20 These and other objects I attain in an apparatus embodying the features herein described and illustrated.

25 In the drawings accompanying this application and forming a part thereof the figure is a sectional view of a transformer embodied in my invention.

30 A primary coil 3, mounted on an annealed wire core 4, is inclosed within a cylindrical fiber casing 5 on which secondary coils 6 and 7 are mounted. The coils are inclosed within a shell 8, which is provided with a fiber bottom portion 9 and a fiber top portion 10 which is connected to the casing 8 by suitable screws 11.

35 Secondary terminal screws 12 and 13, primary terminal screws 14 and 15 and a condenser terminal 16 are mounted on the top portion 10. The lower end of the annealed wire core 4 is mounted in a cylindrical recess 17 of a fiber bush 18, which is attached to the fiber casing 5. The casing 5 is supported by the bottom portion 9 and is held in place by a cylindrical recess 19. The fiber top portion 10 of the inclosing casing is provided with a recess 21 by which the upper end of the iron core and the fiber casing 5 are held in place.

40 The inclosing shell 8 is adapted to be filled with transformer oil and each end of the casing 5 is provided with annular rows of holes 22 which permit of a circulation of oil around the primary coil 3 since considerable clearance is maintained between the sur-

face of the coil and the interior surface of the casing 5.

55 A condenser 23, (shown diagrammatically) and which in practice may consist of any well known construction, is connected between the wires 24 and 25, in parallel with the secondary coils 6 and 7 which are in 60 series in the circuit. The portion of the wire 24 adjacent to the coils 6 and 7 is provided with a glass insulating tube 26. The condenser 23, in parallel with coils 6 and 7, gives a fatter or heavier spark than the same 65 coils would give without a condenser.

The advantage of using transformer oil in combination with the shell 8 and the fiber casing 5 is that convection currents are set up within the casing causing the oil to circulate through and around the coils and the shell 8 materially aids in carrying off the heat by radiation. The viscosity of the transformer oil is low and it therefore proves a valuable auxiliary in insulating the coils 75 since if a break in the insulation does take place and a spark jumps across it the oil at once fills the gap and the insulation is renewed; and since the transformer oil does not carbonize when subjected to an electric 80 spark no serious difficulties are encountered.

Having now described my invention, what I desire to secure by Letters Patent is:

1. In a transformer the combination of a primary coil, a casing, a secondary coil surrounding said casing to permit a circulating space, an outer shell a cooling and insulating liquid in the outer shell surrounding said coils, and ports located in said casing whereby a circulation of liquid may be had 90 through the space between the primary coil and said casing by convection currents when the coils are energized.

2. In a transformer the combination of a primary coil, a metallic core therefor, a casing spaced away from the primary coil but surrounding it, a secondary coil on the casing, a shell surrounding said coils, said casing having ports at its ends whereby a circulation of cooling and insulating liquid 100 may be had within said shell and between said coils due to convection currents when the coils are energized.

3. In a transformer the combination of a primary coil, a vertically extending tubular 105 casing surrounding said coil and spaced

from it, a secondary coil mounted on said casing, said casing having ports at its respective ends, a shell inclosing both of said coils and containing a cooling and insulating liquid adapted to circulate through the ports and between the tubular casing and the first mentioned coil.

In testimony whereof, I have hereunto subscribed my name this 13th day of February, 1906.

MARK B. ORIST.
